UNITED STATES PATENT OFFICE.

WILLIS W. PALMER, OF JERICHO, VERMONT.

MAIL-BOX.

No. 882,709.

Specification of Letters Patent. Patented March 24, 1908.

Application filed June 9, 1906. Serial No. 321,035.

To all whom it may concern:

Be it known that I, WILLIS W. PALMER, a citizen of the United States, residing at Jericho, in the county of Chittenden and State of Vermont, have invented certain new and useful Improvements in Mail-Boxes Especially Designed for Rural Collections, of which the following is a specification, reference being had therein to the accompanying drawing.

My invention relates to improvements in mail boxes, pertaining more particularly to those in rural free delivery districts.

The object of my invention is to provide a mail box of the character described, in which the mail or money which is often placed in the box, may be readily removed from the box without removing it by hand through the upper end.

Another object of my invention is to provide a box of this character, which is so constructed to work in conjunction with a receptacle, whereby the contents are readily emptied from the mail box to the receptacle, and thus with certainty the contents of the mail box is deposited in the receptacle, and from there emptied into the mail bag.

A still further object of my invention is to provide a more simple, cheap and effective mail box, and means for removing the contents therefrom.

In the accompanying drawings, Figure 1, is a perspective view of my mail box and receptacle separated. Fig. 2, is a transverse vertical sectional view of my device showing the receptacle in position, and showing in dotted lines the position it assumes when removing the mail. Fig. 3, is a perspective view of the swinging bottom.

Referring now to the drawings, 1 represents a post or other support to which the box 2 is secured in any well known manner, and said box 2 is, as shown, of a rectangular form having a cover 3 hinged at the upper edge adjacent the post, as indicated at 4. Pivotally carried by one end of the box is an arm 5 which swings parallel with the end of the box, and adjacent thereto. The outer end of said arm carries a plate 6 which is painted white or other color for the purpose herein-after more fully described. The cover 3, adjacent its forward end, is provided with an

outwardly extending lug 7 which is adapted to engage the arm 5 of the signal, and throw the same upwardly past a vertical position, 55 and a stop 8 carried by the side of the box limits the backward movement of the arm and thus holds the signal in a vertical position. It will be seen by this structure, that when the cover is swung upwardly to deposit 60 mail in the box, the signal arm is raised and left raised to indicate to the carrier or collector that there is mail in the box to be collected.

The hinge connection 4 between the box 65 and the cover is made by having the upper end of the box rolled, and having a pin 9 rolled therein, and the cover carrying the hinge members passes through the slots and around the pin. The bottom 10 of the box 70 is hinged to the box as at 10'. The bottom 10 is of a box-like form having end walls 11 and 12, and a rear wall 13 which extends within the box, and thus form a tight connection with the box. The front portion of 75 the bottom is open at 13', and extending from a point adjacent thereto to the rear wall, are the inclined fins 14 upon which the mail rests, and tend to direct the letters forwards towards the open front end of the 80 bottom.

The ends of the box adjacent the front side are provided with oppositely arranged segmental slots 15, and the bottom 13 is provided with studs 17 and 18 which extend 85 outward through the segmental slots and are provided with the operating knobs 19 and 20. The bottom is held in its normal upward position by springs, as will be hereinafter fully described, and the studs 17 and 18 are 90 normally held within the upper end of the slots when the bottom is closed. By pressing down upon the knobs 19 and 20 it will be seen that the bottom is swung downwardly.

In order to normally hold the bottom in 95 its upward position within the box, I provide springs, as heretofore stated. These springs 21 are leaf-springs riveted to the rear side of the box, and extending down over the rear wall 13 of the bottom on the inside, and thus bearing against the same and holding the bottom in its upward position. When the bottom is forced downward, as heretofore explained, and the rear wall 13 of the

bottom is drawn outward against the springs, and when the bottom is released, the springs throw the same upwardly in its normal closed position.

- 5 The receptacle 22 for working in conjunction with the mail box, consists of a rectangular scoop-shaped member having the closed upper end 23, and the end wall having the oblique portion 24 and 25. The said oblique portions are provided with notches 26 which incline slightly downwardly. The rear wall of the receptacle is provided with a handle 27 by means of which it is readily handled.
- 10 In operation, the receptacle is placed in a position wherein it receives the front lower corner of the mail box with the slots extending over the studs 17 and 18, and when in this position it will be seen that the bottom 20 of the receptacle is below the outer end of the bottom of the box, and by taking hold of the ends of the receptacle and pressing down upon the knobs, the bottom, together with the receptacle is forced downward and the 25 contents of the box discharged into the receptacle, and it can be readily transferred to the ordinary mail bag. By this construction and operation, it will be seen that the contents of the box is readily discharged 30 without the necessity of removing the mail by hand. In rural free delivery districts the mail is often placed in the box without postage, and the money also placed in the box, and in such cases, in cold weather it is very 35 inconvenient to remove the contents of the box by hand through the top. By this structure, it will be seen that the contents are readily removed without the liability of dropping the same, as it is not handled at all 40 by hand.

The front wall of the box is provided with a shield 28 which extends downwardly, and engages the upper face of the bottom, and thus serves as an additional means for preventing the mail or money from sliding out 45 of the bottom.

Having thus described my invention, what I claim and desire to secure by Letters Patent, is:—

50 1. The combination with a mail box having a hinged bottom, studs carried by the bottom, and a receptacle adapted to engage said studs and to work in conjunction therewith for opening the bottom and receiving 55 the mail from the box.

2. The combination with a mail box having a hinged bottom, studs carried by the bottom, and a receptacle having notches to receive the studs whereby the bottom is 60 opened for discharging the contents of the box into the receptacle.

3. The combination with a mail box having a hinged bottom, studs carried by the bottom and extending through slots in the

box, and a receptacle having notches to receive said studs whereby the bottom is moved downwardly with the receptacle for discharging the contents of the box therein. 65

4. The combination with a mail box having a hinged normally spring-closed bottom, 70 studs carried thereby, and a receptacle having notches to receive the studs, whereby the bottom is opened for discharging the contents of the box into the receptacle.

5. The combination with a mail box having a hinged normally spring-closed bottom, inclined fins or ribs carried by the bottom for guiding the mail towards the forward end of the box, studs carried by the bottom and projecting through segmental slots in the 80 box, and a receptacle having notches to receive the studs, whereby the bottom and receptacle are moved downwardly together for discharging the contents of the box into the receptacle. 75

6. The combination with a mail box having a hinged box-like bottom, springs riveted to the box and bearing against the rear vertical wall of the bottom, and normally holding the bottom in its upward closed position, 90 studs carried by the bottom, and a receptacle adapted to fit over the lower end of the box and having notches to receive the studs, whereby the bottom and receptacle are moved downwardly together for discharging 95 the contents of the box into the receptacle. 85

7. A mail box comprising a box, a hinged cover therefor, a box like bottom hinged at the rear side and adapted to pass within the box, springs riveted to the box and bearing 100 against the rear vertical wall of the bottom and normally holding the bottom in an upward position.

8. The combination with a mail box having a hinged box like bottom, springs riveted 105 to the box and bearing against the rear vertical wall of the bottom and normally holding the bottom in its upward closed position, studs carried by the bottom and extending through the segmental slots in the box, 110 knobs carried by the studs on the outside of the box, and a receptacle adapted to fit over the lower end of the box and having notches to receive the studs, whereby the bottom and receptacle are moved downward together for discharging the contents of the 115 box into the receptacle. 120

9. The combination with a mail box, a hinged bottom normally held in its upper closed position, studs carried by the bottom 120 and projecting through segmental slots in the box, knobs carried by the studs on the outside of the box, and a receptacle having notches to receive the studs, whereby the bottom and receptacle are moved downward together for discharging the contents of the 125 box into the receptacle.

10. A mail box, comprising a box, a hinged

cover therefor, a box-like bottom hinged at the rear side and adapted to pass within the box, means for holding the bottom in its upward position, studs carried by the bottom and projecting through segmental slots in the box, and a receptacle having notches to receive the studs, whereby the bottom and receptacle are moved downwardly together

for discharging the contents of the box into the receptacle.

In testimony whereof I do affix my signature in presence of two witnesses.

WILLIS W. PALMER.
